L. M. TOPOOSIAN

FLASH LIGHT

Filed Sept. 17, 1923

Fig. 3.

INVENTOR.
Leon M. Topoosian.

Harry W. Brown.
ATTORNEY.

UNITED STATES PATENT OFFICE.

LEON M. TOPOOSIAN, OF SPRINGFIELD, MASSACHUSETTS.

FLASH LIGHT.

Application filed September 17, 1923. Serial No. 663,168.

To all whom it may concern:

Be it known that I, LEON M. TOPOOSIAN, a citizen of the United States of America, residing at Springfield, county of Hampden, 5 Commonwealth of Massachusetts, have invented certain new and useful Improvements in Flash Lights, of which the following is a specification.

This invention relates to improvements in 10 electric flash light lamps.

An object of the invention is to provide an electric lamp which may be used for several purposes, first, as the usual or common flash light; second as a device for testing 15 fuses in order to determine whether or not the fuse is a perfect one and third; as a device for testing or locating grounds of an electric machine, circuit, motor or dynamo.

A particular object of my improvement is 20 to provide a convenient electric light whereby a workman may conveniently use both of his hands in making overhead repairs or installations of various kinds of apparatus and devices as overhead shafting constructions, 25 or electric wiring or other fixtures.

The improvement, in general, comprises the usual tubular casing, or member, in 30 which the battery cell is located, the electric bulb and reflector at one end of the casing and a switch for opening or closing the electric circuit. In addition to these parts there is provided devices for the objects referred to above.

Referring to the drawings which form a 35 part of the specification,

Fig. 1 is an external elevational view showing the complete lamp.

Fig. 2 is a sectional view on the line 2—2 of Fig. 1 through the axis of the casing 40 showing the interior construction and assemblage of the various parts of the device, and in dotted lines the lamp part and its connections removed.

Fig. 3 is a detail view of the lens and cap 45 at one end.

Fig. 4 is a detail view of the base piece which receives the lamp.

Fig. 5 is a detail bottom plan view of Fig. 4 looking from the right.

Fig. 6 is a detail top plan view of Fig. 4 looking from the left.

Fig. 7 is a detail sectional view on the line 7—7 of Fig. 6.

Fig. 8 is a top view of the insulating cap, 55 and

Fig. 9 is a detail sectional view of Fig. 8 on the line 9—9 of Fig. 8.

Referring to the drawings in detail:

1 designates the metallic enclosing casing member of the lamp, 2 the usual dry battery cell therein, the negative terminal of which may be indicated at 3 which rests against a spring 4 that is attached to the internally threaded closing cap 5, whereby the metallic casing is electrically connected to the battery. 6 designates a cup-shaped insulating member which is located in the opposite end of the metallic casing 1. This member is attached to the casing by means of the screws 7 and 8 which pass through openings 60 in the block of insulating material 9.

Attached to the block 9 is a rotatable part 10 by means of the screw 11 which passes through the block 9 and its inner end 11' contacts with the metal plate 12 which is located on and attached to the cup-shaped insulating member 6 by means of the screws 13. 14 is a slideable circuit closer thumb piece which is attached to the contact plate 15 by means of the two screws 16; which 65 move in the openings 17 of the casing 1, as shown. When the thumb piece 14 is moved forward the contact plate 15 engages the metal plate 12. Connected to the plate 12 is a screw 18 see Fig. 9, the head of which 70 secures one end of the electric insulated wire 19; the other end of the wire is connected under the head of the screw 20 of the block 21 of insulation 21. 22 designates another 75 wire, one end of which is connected to the terminal 23 of the battery 2, its other end is connected to the metallic contact plate 24 by means of the screw 25. The terminal 23 may be considered the positive pole of the battery for convenience in tracing the 80 circuits.

Attached to the block of insulation 21 is a metallic plate 26 with which the end of the screw 20 engages to form an electric contact, for one side of the electric circuit. 100 The electric bulb 27 engages, as shown, the plate 24.

Secured to the block 21, at opposite sides of the same, are two spring clips 28 for the purpose of permitting the lamp 27, and its reflector 29 to be readily attached and detached from the block 21. The clips 28, are secured to the block 21 by the screws 30. 31 is a metallic plate and 32 is a piece of insulation which are secured together and to 105 110

the reflector 29 by the threaded thimble 33, as shown, by bending or crimping its opposite ends.

The block 21 is formed with a reduced inner end in order to fit into the upper end of the cup-shaped member 6 when the parts are assembled as shown in Fig. 2. In this position the wires 19 and 22 are coiled on the reel 34.

For the purpose of preventing the block of insulation 21 from being rotated when the parts are assembled, a pin 35 enters a recess 36 in the upper end of the cup 6 (see Fig. 9).

Attached to the upper threaded end of the casing 1 is the connector piece 37 on its upper edge 38 rests the outer flange part of the reflector 29. 39 is a cap part which is threaded onto the connector piece 37. This carries the usual glass lens 40.

For temporarily attaching the lamp casing to the person, or user, a loop 41 is provided. This is designed to engage a button or buckle of the apparel of the user, whereby he may have both hands free for use.

Located on the under side of the rotatable piece of insulation 9 is a plate 42 (see Figs. 1 and 2). This plate is electrically connected to the screw 11, which as shown, is threaded through the casing 1, that is the negative side of the battery 2. The purpose of this plate is to provide means for making a "ground test," by placing a fuse for example, between the plate 42 and the reflector 29 which includes the two sides or terminals of the battery.

The improvement is used as follows:

When the thumb piece 14 is moved forward the plate 15 will close the circuit by engaging the plate 12, and closes the circuit through the wire 19, screw 20, plate 31, lamp 27, plate 24, wire 22 to the other terminal of the battery. It is now used as an ordinary flash lamp. When the loop 41 is attached to the person so that both hands can be free to use, the lens 40 is removed permitting the lamp 27 and its reflector and the block 21 of insulation to be removed from the cup shaped insulating member as shown in dotted lines in Fig. 2. The wires 19 and 22 permit the lamp to be placed near the work.

When used as a ground or fuse tester the part to be tested is connected or inserted between the plate 42 and the metallic casing 1 whereby the circuit is closed through the lamp 27 causing it to glow if the part, as a fuse, is in perfect condition. If there is an open circuit the lamp will fail to glow.

What I claim is:

1. In an electric flash lamp, the combination, with an enclosing metallic casing, a battery therein having one terminal connected to the casing, an insulating cup-member in the casing, a terminal on said member

and connected to the other terminal of the battery, an electric lamp, a disk shaped base for the lamp, a block of insulating material removably fitted in the open end of said member, clamps on the block for permitting the said base of the lamp to be attached and detached, a switch on the casing, and wires between the switch, the block and the terminals of the battery.

2. In a flash lamp, the combination, with an enclosing casing, a battery in the casing, a cup-shaped member of insulating material secured to the casing, a block of insulating material designed to close the open end of said member, clips on the block, a contact piece on the block to receive the contact end of an electric bulb, a reflector for the lamp, a plate on the reflector for engaging the contact part with the lamp, a disk on the reflector for insulating the plate thereon from the reflector, said disk engaging the clips on the blocks for removably retaining the lamp thereon, and electrical connections between the terminals of the battery, the contact clips on the block and the contact part on the block.

3. In a flash lamp, the combination with a casing member, a battery therein, a cup-shaped member of insulating material secured to the casing, a block for closing the open end of the cup-shaped member, elastic means on the block for permitting an electric bulb to be attached and detached from the block, wires between the terminals of the battery and the terminals of the lamp, said wires being placed in the cup-shaped member when the block is placed on the open end of said member.

4. In a flash lamp, the combination with a casing member, a battery therein, a cup-shaped member secured to the casing, a block for closing the open end of the cup-shaped member, elastic means on the block for permitting an electric bulb to be attached and detached from the block, wires between the terminals of the battery and the terminals of the lamp, said wires being placed in the cup-shaped member when the block is placed on the open end of said member, and a reel on which the wires are wound when placed in the cup-shaped member.

5. A flash lamp comprising a casing member, a battery therein, a cup-shaped member secured to said member, an electric bulb, wires, a removable reel in the receptacle on which the wires are wound when placed in the receptacle and which are connected to the terminals of the battery and the bulb, and a switch for opening and closing the circuit.

6. A flash lamp comprising a casing member, a battery therein, a receptacle secured to said member, an electric bulb, wires in the receptacle which are connected to the termi-

- nals of the battery and the bulb, and a switch for opening and closing the circuit, a block for receiving the bulb and means on the block to permit the lamp to be snapped onto and removed from the block. 5
7. In a flash lamp, the combination with a casing, a battery in the casing, a receptacle in the casing, wires in the receptacle which are connected to the terminals of the battery, an electric bulb to which the wires are connected, means for retaining the bulb on the receptacle, said wires permitting the bulb to be drawn out of the casing, and a reel for coiling the wires thereon for placing them in the receptacle when the bulb is placed on the receptacle. 10
8. An attaching and circuit closing device for an electric bulb comprising a block member of insulating material, a contact strip 20 on the block with which the threaded end of the bulb engages, a contact disk plate on the block, a disk of insulation, and spring clips on the block to removably receive the said disk of insulation. 25
9. An attaching device for electric bulbs comprising, in combination, a reflector in which the bulb is located, a disk of insulation attached to the reflector and through which the threaded stem of the bulb passes, a metal contact plate on the disk of insulation, a threaded thimble having its ends bent over to secure the reflector, the disk of insulation and plate together, a block having an opening through the same to receive the threaded stem of the lamp, a contact plate 30 on the block and with which the stem engages, a second contact plate on the block and with which the metal contact plate on the reflector engages, and spring clips on the block for gripping the edge of the disk of insulation on the reflector, whereby the lamp and reflector may be snapped onto and removed from the block. 35
10. In combination, a flash lamp having an enclosing casing, a battery therein, an electric bulb, electrical connections between the terminals of the battery and the lamp, a movable plate member attached to the casing, and insulated therefrom, the plate being electrically connected to one terminal of the battery, and the casing connected to the other terminal, whereby when a member is inserted between the plate and casing the circuit to the lamp will be closed and the member will be tested for an open or closed 40 circuit. 45
